PUMP

Isaac H. Athey, Chicago, Ill.

Application July 30, 1938, Serial No. 222,077

14 Claims. (Cl. 103—51)

My invention relates to pumps particularly adapted for use in deep oil wells and for similar purposes and has for a general object the provision of a novel and improved pump mechanism whose operation is automatic and is effected by a continuous supply of compressed air or other gas at a constant high pressure.

Another object of my invention is to provide a pump having means for positively discharging oil or other liquid from a pump chamber and additional means for aiding the rise of the liquid to the surface of the ground by lightening the column of oil or other liquid.

Another object of my invention is to provide an efficient pump of simple and economical construction in which a maximum of work is accomplished for any given size of pump.

Another object is to provide a pump having improved and simplified valve mechanism for controlling the operation of the pump.

The invention disclosed herein is an improvement on that disclosed in my prior application Serial No. 85,026 filed June 13, 1936. The instant application is a continuation in part of my said prior application and contains all claims common to the two disclosures.

Other objects of my invention will appear as they are hereinafter disclosed and claimed and as set forth in the accompanying drawings 30 wherein

Figure 1A is a longitudinal cross-section of the pump mechanism showing the parts in the positions which they assume when the pump is discharging liquid from the pump cylinder;

Figure 1B is a longitudinal cross-section of the structure forming a continuation of the upper end of Figure 1A;

Figure 2 is a longitudinal cross-section of the pump mechanism showing the parts in the positions they assume during the intake stroke of the pump piston;

Figure 3 is a transverse section through the valve mechanism and is taken on the irregular line 3—3 of Figure 1A;

Figure 4 is a vertical section through the air inlet valve and is taken on the irregular line 4—4 of Figure 3;

Figure 5 is a vertical section through the air discharge valve and is taken on the irregular line 5—5 of Figure 3;

Figure 6 is a transverse section of a gas intake and is taken on the line 6—6 of Figure 1B; and

Figure 7 is a vertical section on the irregular line 7—7 of Figure 6 showing the gas intake.

In the drawings, the small broken arrows indicate the flow of air, the small solid arrows indicate the flow of oil, and the large solid arrows indicate the direction of travel of the piston.

Referring to the drawings, I have indicated the pumping mechanism as being located in the well casing which is designated generally by reference numeral 10. It will be understood that when oil is first struck, the pressure on the oil is usually sufficient to raise this oil to the surface 10 of the ground in sufficient quantities without the addition of any pumping mechanism. With the passage of time the pressure in the well becomes reduced and it is necessary to insert a pump in the casing of the well to bring the oil to the 15 surface of the ground with the desired rapidity of flow. When the pumping mechanism is first inserted in the well casing, the natural level of the oil may be substantially the surface of the ground and as oil is continually withdrawn from 20 the well, the natural level of the oil recedes so that at suitable intervals the pumping mechanism must be lowered farther and farther down the casing of the well. As a general rule I preferably locate the pumping cylinder about a hundred 25 feet below the natural level of the oil in the well, although it is to be understood that this may be varied within any desired limits to conform to particular conditions or personal ideas with respect to the proper location of the 30 pump cylinder, as my improved pump may be located either immediately adjacent the surface of the oil or any suitable distance therebelow.

My novel pump comprises a pump cylinder 12 having an inlet check valve 14 adjacent its lower 35 end, the check valve being composed of a ball 16 and seat 18, the upper surface of the seat being so inclined that the ball will roll by gravity into position to close the opening through the seat 18. The upper end of the cylinder 12 is 40 closed by a head 20 which contains the inlet and discharge valves for the air or other operating fluid.

A piston 22 is reciprocably located in the pump cylinder 12 and carries a reciprocable discharge 45 tube 24 through which the oil is discharged from the pump cylinder 12. This discharge tube has rigidly attached thereto, by threading or other suitable means, a second piston 26 of smaller diameter than the piston 22 and located in an 50 air cylinder 28 which is threaded or otherwise attached to the head 20.

The upper end of the reciprocable discharge tube 24 is in sealed telescopic relationship with a stationary discharge tube 30 which leads to the 55

surface of the ground and through which the oil is discharged. The lower end of this discharge tube is threaded or otherwise secured to a second head 32 which is also in sealed engagement with the upper end of the air cylinder 28. The stationary discharge tube 30 is provided with a valve seat 34 located at a point just above the uppermost position reached by the upper end of the reciprocable discharge tube 24. A gravity-actuated ball valve 36 cooperates with the valve seat 34 to permit the upward discharge of oil therethrough but to prevent flow in the reverse direction.

The compressed air or other gas for operating the pump is supplied through an air tube 38 which surrounds the discharge tube 30 and which is attached at its lower end to the head 32 as by threading or any other suitable means. The air tube 38 surrounds and is of larger diameter than the discharge tube 30 so that a space is provided therebetween through which the compressed air passes to the pumping mechanism. At suitable intervals in its length the stationary discharge tube 30 is provided with gas intakes indicated generally by reference character 40. Each gas intake comprises a valve member 42 suitably secured to the discharge tube 30 as by screws 44 and provided with a tapered end 46 forming the valve proper and normally adapted to close the opening 48 in the discharge tube 30.

The valve member 42 is normally so biased that its tapered end 46 tends to move outwardly to uncover the opening 48 but this tapered end is normally held in closing position by the pressure of the compressed air acting on the outer surface of the tapered end of the valve member 42. The biasing of the valve member 42 can be set for any desired degree of bias by means of the adjusting screw 50. When the weight of the column of oil in the discharge tube 30 becomes great enough to exert a force on the inner surface of the tapered end 46 of valve member 42 to nearly balance the air pressure acting on the outer surface of this tapered end, the valve member 46 moves away from its seat and permits compressed air to flow into the discharge tube 30. The air thus admitted to the discharge tube 30 forms air bubbles in the oil above the opening 48, thus lightening the column of oil thereabove and reducing the force which must be exerted by the pump piston 22 to raise the oil to the surface of the ground.

On each side of the gas intake valve 42 I preferably locate spacer members 52. These spacer members 52 provide sufficient local clearance between the discharge tube 30 and the air tube 38 to permit the necessary movement of the tapered end 46 of valve member 42. It will be understood that the gas intakes 40 are located at suitable intervals along the discharge tube 30 and that the number of such gas intakes increases as the pump is lowered in the well.

The compressed air or other gas forced down the air tube 38 passes through suitable openings 54 in the head 32 to the annular space 56 provided between the air cylinder 28 and a sleeve 58 which surrounds this air cylinder in spaced relationship thereto. The lower end of this space 56 communicates with the yoke-shaped ports 60 which cooperate with the inlet valve 62 for controlling admission of air to the upper end of pump cylinder 12 and to the air cylinder 28.

As best shown in Figure 4, the yoke-shaped ports 60 have lower outlets 64 adapted to communicate with vertical passage 66 when the inlet

valve 62 is in the position shown in Figure 4. When the valve 62 is shifted to its other extreme position, the central rectangular portion of the valve cuts off communication between outlets 64 and the passage 66 and simultaneously opens communication between the upper outlets 68 and passage 70 leading to the lower end of air cylinder 28.

The extreme positions of the valve member 62 are determined by washers 72 and 74 which are held in place by nuts 76 and 78 respectively. The passages 66 and 70 are rectangular in cross-section so that the washers 72 and 74 overlie the sides of these passages and contact respectively with the lower and upper sides of the head 20. The valve member 62 is held in either of its two extreme positions by the differential air pressures acting on opposite sides thereof. I shall presently describe the means for shifting the valve member between its extreme positions.

When the air inlet valve 62 is in the position shown in Figures 1 and 4, the compressed air is admitted to the upper end of the pump cylinder 12 above the piston 22. This drives the piston 22 and discharge tube 24 downward as indicated by the large arrow in Figure 1. The check valve 14 at the lower end of the pump cylinder is closed and the oil beneath the piston 22 is forced upwardly through discharge tube 24, check valve 34, and rigid discharge tube 30, as indicated by the small solid arrows in Figures 1A and 1B.

At the same time, the smaller piston 26 is moving downwardly and discharging the air therebeneath through the air discharge valve mechanism located in the head 20 and into the annular space 80 between the well casing 10 and the outside of the pump cylinder 12, head 20 and sleeve 58, this annular space preferably averaging about a quarter of an inch.

As best shown in Figures 3 and 5, the air discharge valve mechanism comprises a reciprocable valve member 82 having rectangular passage closing portions 84 and 86. During the discharge stroke of the pump the valve portion 84 is clear of the upper end of the vertical passage 88, thus permitting air to flow from the lower end of the air cylinder 28 into this passage and thence through lateral ports 90 to the annular space 80. At the same time the lower valve portion 86 closes communication between the lower end of the passage 88 and the upper end of the pump cylinder 12. The force of the air beneath the lower end of the valve member 82 holds the annular washer 92 in engagement with the lower side of the head 20 where this washer overlaps the sides of the rectangular passage 88. The washer 92 is secured to the valve member 82 by nut 94. The upper end of the valve member 82 is similarly provided with an annular washer 96 and nut 98 which limit the downward movement of the valve member when shifted in a manner to be presently described.

When the piston 26 approaches the lower end of its stroke, the nuts attached to the upper ends of the valve members 62 and 82 are engaged by the coil spring 100 which functions to shift these valve members to their other extreme positions as the piston reaches the downward limit of its stroke. The spring 100 is formed of a flat strip of spring metal and is suitably secured to the air piston 26 for reciprocation therewith.

After the air valve members 62 and 82 have been thus shifted, they assume the position shown in Figure 2. In this position of these valves, compressed air is admitted to the lower end of

air cylinder 28 where it acts on the underside of piston 26 to raise this piston, the reciprocable discharge tube 24 and piston 22 thereby sucking oil into the pump cylinder 12 through the oil inlet valve 14 as indicated in Figure 2. It will be noted that air cylinder 28 and piston 26 are of smaller diameter than pump cylinder 12 and piston 22 so that a smaller quantity of air suffices to operate the pistons on the oil intake stroke. 10 This results in a material saving since less power is needed to operate the pumping mechanism on this stroke.

During the upward stroke of pistons 22 and 26 the air in the upper end of the pump cylinder 12 is discharged through passages 88 and 90 into the annular space 80 surrounding the pump cylinder and sleeve 58. During the upward stroke of the pistons the air in the space 102 between the air piston 26 and the head 32 is compressed. 20 This space 102 is made of such length that in the normal operation of the mechanism the air in this space expands and contracts as the piston 26 falls and rises. The passage 104 which connects the upper end of the space 102 with the 25 annular space 106 between the well casing and the air tube 38 is provided with a check valve 108 having a relatively strong spring which normally maintains this check valve in closed position during both strokes of the piston 26. The 30 sole purpose of the check valve 108 is to act as a relief valve to prevent the pump from becoming locked due to leakage of air past the piston 26. In case sufficient leakage of air occurs past the piston 26 to raise the pressure in the space 102 appreciably above that normally existing therein when the piston 26 is at the upper limit of its 35 stroke, the valve 108 will open as indicated in Figure 2 to release this excessive pressure.

As the pistons 22 and 26 approach the upper 40 end of their stroke, the spring 110 engages the lower ends of valve members 62 and 62 and raises these valve members to their extreme upward positions, as shown in Figure 1, whereupon the direction of travel of the pistons is reversed. As 45 previously explained, the valve members 62 and 62 are so arranged with respect to their cooperating ports, that these valve members are held in either of their extreme positions by the differential pressures acting thereon.

The operation of my improved pumping mechanism is entirely automatic. All that is necessary is to turn on the compressed air, whereupon the pump will continue to operate until the compressed air is again cut off. Due to the simplicity and ruggedness of the parts, my improved 50 pump is extremely durable and requires a minimum of attention. My pump also has the advantage of being extremely economical in its utilization of the compressed air or other operating gas.

When the parts are in the positions shown in Figures 1A and 1B and the compressed air is turned on, the compressed air flows down the space between the air tube 38 and the discharge tube 80, through the passages 54 in head 32, through the annular space 56 and through ports 60 and 64 and passage 66 to the upper end of pump cylinder 12. The air thus admitted to the pump cylinder forces down the piston 22, whereupon the oil in the pump cylinder is forced upwardly through the reciprocable discharge tube 24, past valve 34, and through discharge tube 80 to the surface of the ground where it may be stored in tanks or otherwise suitably disposed of. 70 As the oil piston 22 descends, the air piston 26

likewise descends, the air ahead of the piston being discharged through passages 88 and 90 into the annular space between the pumping mechanism and the casing of the well. As the piston 26 descends, the air in the space 102 thereabove expands, thereby reducing the pressure existing in this space. 5

As the pistons 22 and 26 approach the lower ends of their stroke, the spring 100 shifts the valve members of the air inlet and discharge valves, thereby admitting air under pressure to the lower end of the air cylinder 28 and permitting the discharge of air from the upper end of the pump cylinder 12 into the annular space 80. As the pistons 22 and 26 move upwardly, oil is 15 drawn in from the well, through the check valve 14 as shown in Figure 2. During the upward stroke of the pistons, the air in the space 102 is compressed, but under ordinary circumstances the compression of this air even at the extreme 20 upward position of the piston 26 is not sufficient to open the check valve 108. When the pistons 22 and 26 approach the upper ends of their stroke, the spring 110 engages the lower ends of the 25 air inlet and discharge valves and shifts them back to the positions shown in Figure 1A, whereupon the cycle is repeated.

When the pumping mechanism is located a considerable distance below the surface of the ground and the pressure of the column of oil above any one or more of the gas intakes 48 becomes sufficiently great, the tapered ends 46 of the valve members 42 move to open position and admit compressed air which forms bubbles in the column of oil thereabove and thus lightens 35 this column, thereby reducing the force which the pump piston 22 must exert to raise the oil to the surface. 30

During the pumping operation it is only necessary that my novel pump be connected to a 40 source of air or other gas under sufficient pressure to raise the oil or other liquid to the surface of the ground. Its operation thereafter is entirely automatic, requiring no attention or external operation whatsoever. In the event that 45 the pressure in the well itself is sufficient to raise the oil or other liquid to the surface without aid from the pump, the air supply may be cut off, whereupon the oil or other liquid itself will open the check valves 14 and 34 and flow to the surface. 50

While my invention is primarily designed for use in oil wells and has been so described, its use is not so limited and it may be used in other types of wells. My invention is not limited to the details shown and described, but may assume numerous forms within the scope of the appended 55 claims.

I claim:

1. In a pump mechanism for wells having casings, the combination of a liquid cylinder and a gas cylinder having a common head, a piston in each cylinder, a reciprocable discharge tube connecting said pistons and extending through said head, a second head at the upper end of said gas cylinder, a rigid discharge tube connected to said last-named head and telescoping with said first-named discharge tube, inlet and discharge valves for said liquid cylinder, a gas conduit surrounding said rigid discharge tube and gas cylinder, a valve for connecting said gas conduit alternately with said cylinders, said gas conduit and pump cylinder being spaced from the well casing, a discharge valve for connecting said cylinders alternately with the space thus formed, 75

5 a spring reciprocable with each piston for shifting said gas inlet and discharge valves, said last-named valves being located in said first-named head and being designed to be held in either extreme position by the differential pressures acting 10 on opposite sides thereof, and a relief valve for said gas cylinder.

10 2. In a pump mechanism for wells having casings, the combination of a liquid cylinder and a gas cylinder having a common head, a piston in each cylinder, a reciprocable discharge tube connecting said pistons and extending through said head, a second head at the upper end of said gas cylinder, a rigid discharge tube connected 15 to said last-named head and telescoping with said first-named discharge tube, inlet and discharge valves for said liquid cylinder, a gas conduit surrounding said rigid discharge tube and gas cylinder, a valve for connecting said gas conduit alternately with said cylinders, said gas conduit and pump cylinder being spaced from the well casing, and a discharge valve for connecting said cylinders alternately with the space thus formed, a spring reciprocable with each piston for shifting said gas inlet and discharge valves, said valves being located in said first-named head and being designed to be held in either extreme position by the differential pressures acting 20 on opposite sides thereof.

25 30 3. In a pump mechanism for wells having casings, the combination of a liquid cylinder and a gas cylinder having a common head, a piston in each cylinder, a discharge tube connecting said pistons and extending through said head, a second head at the upper end of said gas cylinder, a rigid discharge tube connected to said last-named head and telescoping with said first-named discharge tube, inlet and discharge valves for said liquid cylinder, a gas conduit surrounding said rigid discharge tube and gas cylinder, a valve for connecting said gas conduit alternately with said cylinders, said gas conduit and pump cylinder being spaced from the well casing, a discharge valve for connecting said cylinders alternately with the space thus formed, and a spring 35 reciprocable with each piston for shifting said gas inlet and discharge valves, said valves being located in said first-named head and being designed to be held in either extreme position by the differential pressures acting 40 on opposite sides thereof.

40 45 4. In a pump mechanism for wells having casings, the combination of a liquid cylinder and a gas cylinder having a common head, a piston in each cylinder, a discharge tube connecting said pistons and extending through said head, a second head at the upper end of said gas cylinder, a rigid discharge tube connected to said last-named head and telescoping with said first-named discharge tube, inlet and discharge valves for said liquid cylinder, a gas conduit, a valve for connecting said gas conduit alternately with said cylinders for supplying pressure fluid to the sides of the pistons facing the common head, a discharge valve for connecting said cylinders alternately with a gas outlet, and a relief valve for said gas cylinder.

50 55 5. In a pump mechanism for wells having casings, the combination of a liquid cylinder and a gas cylinder having a common head, a piston in each cylinder, a discharge tube connecting said pistons and extending through said head, a second head at the upper end of said gas cylinder, a rigid discharge tube connected to said last-named head and telescoping with said first-

5 named discharge tube, inlet and discharge valves for said liquid cylinder, a gas conduit, a valve for connecting said gas conduit alternately with said cylinders, said gas conduit and pump cylinder being spaced from the well casing, a discharge valve for connecting said cylinders alternately with the space thus formed, and spring means 10 for shifting said air inlet and discharge valves, said valves being located in said first-named head and being designed to be held in either extreme position by the differential pressures acting on opposite sides thereof.

15 6. In a pump mechanism for wells having casings, the combination of a liquid cylinder and a gas cylinder, a piston in each cylinder, inlet and discharge valves for said liquid cylinder, a gas supply conduit, a valve for connecting said gas conduit alternately with said cylinders, said gas conduit and pump cylinder being spaced from the well casing, a discharge valve for connecting said cylinders alternately with the space thus formed, a spring reciprocable with each piston for shifting said gas inlet and discharge valves, said valves being designed to be held in either extreme position by the differential pressures acting on opposite sides thereof, and a relief valve for said gas cylinder.

20 25 7. In a pump mechanism for wells having casings, the combination of a liquid cylinder and a gas cylinder having a common head, a piston in each cylinder, a reciprocable discharge tube connecting said pistons, a second head at the upper end of said gas cylinder, a rigid discharge tube connected to said last-named head and telescoping with said first-named discharge tube, inlet and discharge valves for said liquid cylinder, a gas conduit, a valve for connecting said gas conduit alternately with said cylinders, a discharge valve for said cylinders, and a spring comprising a coil of flat material and surrounding said reciprocable discharge tube.

30 35 8. In a pump mechanism of the class described, the combination of a pair of cylinders, a common head for said cylinders and an inlet valve located in said head, said inlet valve comprising a passage passing entirely through said head, said passage having end portions which are rectangular in cross-section, a transverse passage connecting said first-named passage with a source of gas under pressure, and a valve member located in said first-named passage and having end portions of rectangular cross-section to conform to the ends of said first-named passage, a central portion of reduced cross-section, and a circular member attached to each rectangular portion, said circular members overlapping the sides of said first-named passage whereby said circular members limit the movements of said valve member.

40 45 9. In a pump mechanism of the class described, the combination of a pair of cylinders, a head common to said cylinders, and a discharge valve for said cylinders located in said head, said discharge valve comprising a passage of rectangular cross-section extending through said head, a yoke-shaped passage in said head connecting said first-named passage with a discharge outlet, and a valve member movable in said first-named passage, said valve member having an enlarged section of rectangular cross-section for controlling communication between said first-named passage and said yoke-shaped passage, reduced end portions, and a circular member attached to each end and overlapping the sides of said first-named passage whereby said circular mem- 75

bers limit the movements of said valve member.

10. In a pump mechanism of the class described, the combination of a pair of cylinders, a head common to said cylinders and a discharge valve for said cylinders located in said head, said discharge valve comprising a passage extending through said head, a yoke-shaped passage in said head connecting said first-named passage with a discharge outlet, and a valve member movable in said first-named passage, said valve member having an enlarged section for controlling communication between said first-named passage and said yoke-shaped passage, reduced end portions, and a stop member attached to each end and overlapping the sides of said first-named passage whereby said stop members limit the movements of said valve member.

11. In a pump mechanism of the class described, the combination of a pair of cylinders, a common head for said cylinders, an inlet valve located in said head, said inlet valve comprising a passage passing entirely through said head, said passage having end portions which are rectangular in cross-section, a transverse passage connecting said first-named passage with a source of gas under pressure and a valve member located in said first-named passage and having end portions of rectangular cross-section to conform to the ends of said first-named passage, a central portion of reduced cross-section, and a circular member attached to each rectangular portion, said circular members having a diameter greater than the shorter side of the ends of said first-named passage whereby said circular portions limit the movements of said valve member, and a discharge valve for said cylinders located in said head, said discharge valve comprising a passage of rectangular cross-section extending through said head, a yoke-shaped passage in said head connecting said first-named passage with a discharge outlet and a valve member movable in said first-named passage, said valve member having an enlarged section of rectangular cross-section for controlling communication between

said first-named passage and said yoke-shaped passage, reduced end portions, and a circular member attached to each end and overlapping the sides of said first-named passage whereby said circular members limit the movements of 5 said valve member.

12. In a pump mechanism of the class described, the combination of a pair of cylinders, a head common to said cylinders, inlet and discharge valves for said cylinders located in said head, a piston reciprocable in each cylinder, a spring carried by each piston and adapted to engage and shift said valves, and means carried by said valves to limit the movement thereof under the influence of said springs. 10

13. In a pump mechanism of the class described, the combination of a pair of cylinders, a head common to said cylinders, inlet and discharge valves for said cylinders located in said head, a piston reciprocable in each cylinder, a 20 coiled spring formed of flat material carried by each piston and adapted to engage and shift said valves, and means carried by said valves to limit the movement thereof under the influence of said springs. 15

14. In a pump mechanism for wells having casings, the combination of a liquid cylinder and a gas cylinder having a common head, said gas cylinder being of smaller diameter than said liquid cylinder, a piston in each cylinder, a discharge tube connecting said pistons and extending through said head, a second head at the upper end of said gas cylinder, a rigid discharge tube connected to said last-named head and telescoping with said first-named discharge tube, inlet and discharge valves for said liquid cylinder, a gas conduit, a valve for connecting said gas conduit alternately with said cylinders for supplying pressure fluid to the sides of the pistons facing the common head, a discharge valve for connecting said cylinders alternately with a gas outlet, and a relief valve for said gas cylinder. 25 30 35 40 45
